CLAIM

The ornamental design for a wildlife guard for high voltage bushing, as shown and described.

DESCRIPTION

FIG. 1 is a perspective view from the bottom of the wildlife guard for high voltage bushing of the present invention.

FIG. 2 is a top plan view thereof.

FIG. 3 is a front elevation view thereof.

FIG. 4 is a side elevation view thereof. The left and right side views are identical.

FIG. 5 is a rear elevation view thereof; and,

FIG. 6 is a bottom plan view thereof.
